UNITED STATES PATENT OFFICE.

ERNEST E. LAMBERT, OF INDIAN ORCHARD, MASSACHUSETTS.

SMASH PREVENTER.

Application filed April 29, 1926. Serial No. 105,461.

This invention relates to smash preventers for looms of that type not equipped with brakes, and has for one of its objects the provision of a device of this character which 5 shall be adapted to effect the throwing off of the shipper and the stopping of the lay whenever the respective shuttle boxes simultaneously contain a shuttle.

A further object of the invention is the 10 provision of a device of the character stated which can be readily applied to the breast beam and lay of a loom without making any alterations in these or the other parts of the 15 loom.

With the foregoing and other objects in 20 view, the invention consists of the novel construction, combination and arrangement of parts hereinafter fully described and claimed, and illustrated in the accompanying drawings, wherein:

Figure 1 is a top plan view illustrating the application of the smash preventer to the breast beam and lay of a loom,

Figure 2 is a sectional view taken on the 25 vertical plane indicated by the line 2—2 of Figure 1,

Figure 3 is a sectional view taken on the vertical plane indicated by the line 3—3 of Figure 1,

Figure 4 is a view in elevation of the lay and the parts of the smash preventer supported thereby,

Figure 5 is a sectional view taken on the vertical plane indicated by the line 5—5 of Figure 4,

Figure 6 is a bottom plan view of one of the dagger stops, and

Figure 7 is a sectional view taken on the vertical plane indicated by the line 7—7 of Figure 1.

Corresponding and like parts are referred to in the following description, and designated in the several views of the accompanying drawings, by similar reference characters.

In the drawings, 1 designates the breast beam, 2 the lay and 3 the shuttle boxes of a loom. The rear walls and swells or binders of the shuttle boxes 3 are designated 4 and 5, respectively. As these parts are of well known construction a further description thereof is deemed unnecessary.

In accordance with my invention, a shaft 6 forming a part of the shipper controlling mechanism of the loom, is supported from the breast beam by bearing brackets 7. An

arm 8 extending in a rearward direction therefrom, is secured to the shaft 6 by a set screw 9 and has an arcuate rear end portion 8^a. A torsion spring 10 is mounted on the 60 shaft 6 and is connected at its ends to one of the bearing brackets 7 and a collar 11 mounted on the shaft and secured thereto by a set screw 12. The spring 10 tends to rotate the shaft 6 in a direction to exert a 65 constant upward pull on the arm 8. A bracket 13 having a rearwardly extending horizontal member 13^a and a vertical member 13^b, is secured to the breast beam 1 for vertical adjustment with respect thereto by 70 screws 14 which engage the breast beam and pass through vertical slots in the bracket member 13^b. A vertically disposed arcuate lever 15 is connected at its lower end to the bracket member 13^a for movement about a 75 horizontal axis 16, and is provided intermediate its ends with a horizontally disposed pin 17 which contacts with the upper convex edge of the curved end portion 8^a of the lever 8. The lever 15 is limited in its 80 upward movement by a stop 18 and in its downward movement by a stop 18^a, the stops being carried by and extending horizontally from the bracket member 13^a. A latch 19 is pivoted intermediate its ends as at 20 to 85 the upper portion of the lever 15, and its upper free end is yieldingly supported above the upper free end of the lever 15 by a spring 21. The movement of the latch 19 in an upward direction under the influence of the 90 spring 21 is limited by a shoulder 21^a formed on the lever 15 in position for engagement by the lower free end of the latch.

A shaft 22 carrying rearwardly extending daggers 23, is supported from the breast beam 1 by bearing brackets 24. A rearwardly directed arm 25 is secured to the shaft 22 by a set screw 26, and is connected to the lever 15 by an elbow lever 27 and a link 28. The lever 27 is mounted upon the 100 pivot 16 of the lever 15, and an arm thereof is provided with a head 29 having an arcuate slot 30 through which passes a bolt 31 carried by the lever 15. The levers 15 and 27 are arranged in parallel relation, and the stated 105 connection between the same permits their angular relation to be varied. The link 28 is engaged with one of a series of openings 32 in the lever 27 and passes freely through the free end of the arm 25, and a spring 33 110 is mounted on the link between a nut 34 on the latter and between the arm 25. The

openings 32 permit the link 28 to be adjusted with respect to the pivotal axis of the lever 27, and the spring 33 establishes a yielding connection between the arm 25 and lever 27. The daggers 23 are supported in their normally inactive position by set screws 34^a carried by the bearing brackets 24.

The parts of the smash preventer heretofore described normally occupy the relative positions in which they are shown in Figures 2 and 3. When the lever 15 is actuated in a downward and rearward direction it will, due to the connection established between it and the shaft 6 by means of the arm 8 and pin 17, and due to the connection established between it and the shaft 22 by the lever 27, link 28 and arm 25, rock the shafts in directions to throw off the shipper and raise the daggers 23 into operative position, with the result that the loom will stop and the lay held against forward movement. When the lever 15 is released, the spring 10 and daggers 23 will return the parts to their normal positions.

25 Means for actuating the lever 15 whenever the respective shuttle boxes 3 simultaneously contain a shuttle, is carried by the lay 2 and comprises a lever 35 extending forwardly and rearwardly of the lay and connected to 30 the under side thereof at a point intermediate its ends by movement about a horizontal axis 36. The pivot 36 is carried by a bracket 37 which is provided at the rear side of the lay 2 in a vertically disposed boss 38. 35 A vertical rod 39 is slidably supported by the boss 38. A spring 40 exerts a constant downward pressure on the rod 39, and the downward movement of the rod is limited by a nut 41. The rod 39 is pivotally connected as at 42 to the rear end of the lever 35, and due thereto the latter is normally held in a substantially horizontal position. When the lever 35 is in this position, a hook 43 carried by the forward end of the lever 40 is supported out of the path of the front end of the latch 19. A bar 44 extending longitudinally of the lay 2 is pivoted intermediate its ends to the rod 39 as at 45. The ends of the bar 44 pass through vertical 45 slots 46 in brackets 47 which are secured to and depend from the lay 2. Shafts 48 are supported at the front side of the lay 2 by brackets 49. Downwardly and rearwardly extending arms 50 fixed at their front ends to the shafts 48 have their rear ends disposed below the ends of the bar 44. Upwardly and rearwardly extending arms 51 are secured at their lower ends to the shafts 48 and are provided with angular upper terminals 52 which 55 contact with the swells or binders 5 of the shuttle boxes 3. Springs 53 mounted on the shafts 48, connected to collars 54 on the shafts and contacting with the under side of the lay 2, exert constant downward pressure on the arms 50 and constant rearward

pressure on the arms 51 in order to maintain the former out of contact with the bar 44 and the latter in contact with the swells or binders 5 of the shuttle boxes 3.

When the arms 51 are simultaneously moved forwardly, as will occur whenever a shuttle is in each of the boxes 3, the arms 50 are swung upwardly. As the arms 50 are positioned beneath the bar 44 and as the bar is connected to the rear end of the lever 35, this movement of the arms will swing the lever in a direction to depress the front end thereof and carry the hook 43 into the path of the front end of the latch 19, with the result that the hook will contact with the latch during the backward movement of the lay 2. This actuates the shipper throwing off mechanism of which the shaft 6 forms a part and as the result stops the operation of the loom. At the same time the daggers 23 are raised into active position so as to enable them to contact with stops 55 during the forward movement of the lay whereby to effect the stopping of the motion of the lay. The dagger stops 55 are removably secured in brackets 56 by means of set screws 57. The brackets 56 are of angular formation presenting horizontal members 56^a contacting with the under side of the lay 2 and constituting wear plates. The vertical members 56^b of the brackets 56 contact with the front side of the lay 2. The bracket members 56^a and 56^b are connected with their adjacent edges in relatively spaced relation by strap lugs 58 which are of angular formation and which in conjunction with the front edges of the bracket members 56^a constitute supports for the dagger stops 55. Guides 59 extend forwardly from the lower edges of the bracket members 56^b and serve to guide the free ends of the daggers 23 into engagement with the stops 55 when the daggers are in raised or active position. The brackets 56 are secured in place by screws 60.

From the foregoing description, taken in connection with the accompanying drawings, it should be apparent that the smash preventer will not stop the loom during the normal operation thereof, that it will immediately throw off the shipper whenever the respective shuttle boxes simultaneously contain a shuttle, and that it will at the same time stop the movement of the lay. While I have described the principle of operation of the invention, together with the structure which I now consider to be the best embodiment thereof, I desire to have it understood that the device shown is merely illustrative, and that such changes may be made when desired as are within the scope of the invention as claimed.

What is claimed is:—

1. A smash preventer for a loom, comprising a shipper operating shaft journaled on the breast beam, a lever pivoted to the breast

- beam, an arm carried by the shaft and contacting with the lever, a second shaft journaled on the breast beam, daggers carried by the second shaft, means connecting the second shaft to the lever to permit of its operation thereby, dagger stops carried by the lay, and means under the control of the shuttle boxes for operating the lever when the boxes simultaneously contain shuttles.
- 10 2. A smash preventer for a loom, comprising a shipper operating shaft journaled on the breast beam, a lever pivoted to the breast beam, an arm carried by the shaft and contacting with the lever, a second shaft journaled on the breast beam, daggers carried by the second shaft, an arm carried by the second shaft, a member connecting the arm and lever, dagger stops carried by the lay, and means under the control of the shuttle boxes for operating the lever when the boxes simultaneously contain shuttles.
- 15 3. A smash preventer for a loom, comprising a shipper operating shaft journaled on the breast beam, a lever pivoted to the breast beam, an arm carried by the shaft and contacting with the lever, a second shaft journaled on the breast beam, daggers carried by the second shaft, an arm carried by the second shaft, a member connecting the arm and lever, dagger stops carried by the lay, and means under the control of the shuttle boxes for operating the lever when the boxes simultaneously contain shuttles.
- 20 4. A smash preventer for a loom, comprising a shipper operating shaft journaled on the breast beam, a lever pivoted to the breast beam, an arm carried by the shaft and contacting with the lever, a second shaft journaled on the breast beam, daggers carried by the second shaft, an arm carried by the second shaft, a link connected to the arm and adjustably connected to the lever, dagger stops carried by the lay, and means under the control of the shuttle boxes for operating the lever when the boxes simultaneously contain shuttles.
- 25 5. A smash preventer for a loom, comprising a shipper operating shaft journaled on the breast beam, a lever pivoted to the breast beam, an arm carried by the shaft and contacting with the lever, a second shaft journaled on the breast beam, daggers carried by the second shaft, an arm carried by the second shaft, a link connected to the arm and adjustably connected to the lever, dagger stops carried by the lay, and means under the control of the shuttle boxes for operating the lever when the boxes simultaneously contain shuttles.
- 30 6. A smash preventer for a loom, comprising a shipper operating shaft journaled on the breast beam, a bracket secured to the breast beam and having a rearwardly extending member, a lever pivoted to the bracket member, an arm fixed to the shaft and contacting with the lever, an elbow lever journaled on the pivot of said first lever, means adjustably connecting one end of the elbow lever to said first lever, a second shaft journaled on the breast beam above said first shaft, daggers carried by the second shaft, dagger stops carried by the lay, an arm extending rearwardly from the second shaft, a link having an adjustable connection with the other end of the elbow lever and having a slideable connection with the said second arm, a stop carried by the link below the second arm, a spring mounted upon the link between the stop and second arm, and means under the control of the shuttle boxes for operating the first lever when the boxes simultaneously contain shuttles.
- 35 7. A smash preventer for a loom, comprising a shipper operating shaft journaled on the breast beam, a lever pivoted to the breast beam, an arm carried by the shaft and contacting with the lever, a second shaft journaled on the breast beam, daggers carried by the second shaft, dagger stops carried by the lay, an arm extending rearwardly from the second shaft, a link having an adjustable connection with the other end of the elbow lever and having a slideable connection with the said second arm, a stop carried by the link below the second arm, a spring mounted upon the link between the stop and second arm, and means under the control of the shuttle boxes for operating the first lever when the boxes simultaneously contain shuttles.
- 40 8. A smash preventer for a loom, comprising a shipper operating shaft journaled on the breast beam, a lever pivoted to the breast beam, an arm carried by the shaft and contacting with the lever, a second shaft journaled on the breast beam, daggers carried by the second shaft, dagger stops carried by the lay, an arm extending rearwardly from the second shaft, a link having an adjustable connection with the other end of the elbow lever and having a slideable connection with the said second arm, a stop carried by the link below the second arm, a spring mounted upon the link between the stop and second arm, and means under the control of the shuttle boxes for operating the first lever when the boxes simultaneously contain shuttles.
- 45 9. A smash preventer for a loom, comprising a shipper operating shaft journaled on the breast beam, a lever pivoted to the breast beam, a second lever pivoted between its ends to the breast beam and adjustably connected at one end to the first named lever, an arm carried by the shaft and contacting with the first lever, a second shaft journaled on the breast beam, daggers carried by the second shaft, an arm carried by the second shaft, a link connected to the arm and to the other end of the second lever, dagger stops carried by the lay, and means under the control of the shuttle boxes for operating the first lever

when the boxes simultaneously contain shuttles.

6. A smash preventer for a loom, comprising a shipper operating shaft journaled on the breast beam, a lever pivoted to the breast beam, an arm carried by the shaft and contacting with the lever, a yielding latch carried by the lever, and means under the control of the shuttle boxes and adapted to engage the latch to effect the operation of the lever when the boxes simultaneously contain shuttles.

7. A smash preventer for a loom, including a shaft journaled on the breast beam, daggers carried by the shaft, a lever pivoted to the breast beam and embodying adjustably connected sections, an arm carried by the shaft, a link connecting the arm and one of the lever sections, dagger stops carried by the lay, and means under the control of the shuttle boxes and cooperating with the remaining lever section for operating the lever when the boxes simultaneously contain shuttles.

8. A smash preventer for a loom, comprising a shipper operating shaft journaled on the breast beam, a bracket secured to the breast beam and having a rearwardly extending member, a lever pivoted to the bracket member, an arm fixed to the shaft and contacting with the lever, an elbow lever journaled on the pivot of said first lever, means adjustably connecting one end of the elbow lever to said first lever, a second shaft journaled on the breast beam above said first shaft, daggers carried by the second shaft, dagger stops carried by the lay, an arm extending rearwardly from the second shaft, a link having an adjustable connection with the other end of the elbow lever and having a slideable connection with the said second arm, a stop carried by the link below the second arm, a spring mounted upon the link between the stop and second arm, and means under the control of the shuttle boxes for operating the first lever when the boxes simultaneously contain shuttles.

9. A smash preventer for a loom, including a bracket attached to the lay and having vertical and horizontal members and angular strap lugs securing the members together with their adjacent edges in relatively spaced relation, a dagger stop positioned in the strap lugs in contact with the front edge of the horizontal member, a set screw carried by one of the strap lugs and engaging the stop to secure it in place, and a guide carried by the vertical member above the stop.

In testimony whereof I affix my signature.

ERNEST E. LAMBERT.
